UNITED STATES PATENT OFFICE.

EUGENE DE KLEIST, OF NORTH TONAWANDA, NEW YORK.

AUTOMATIC PIANO.

No. 841,787.

Specification of Letters Patent.

Patented Jan. 22, 1907.

Application filed November 16, 1905. Serial No. 287,636.

To all whom it may concern:

Be it known that I, EUGENE DE KLEIST, a citizen of the United States, residing at North Tonawanda, in the county of Niagara 5 and State of New York, have invented a new and useful Improvement in Automatic Pianos, of which the following is a specification.

This invention relates to that class of automatic pianos which are provided with means for rapidly vibrating the hammers so that they strike the strings numerous times for each note and produce a mandolin effect.

The object of my invention is to improve 15 the mandolin-section of the piano-action with a view of simplifying its construction and rendering its parts easy of access for adjusting and repairing purposes.

In the accompanying drawings, consisting 20 of two sheets, Figures 1 and 2 are fragmentary cross-sections of a pneumatically-operated piano-action embodying the invention, showing different positions of the parts. Fig. 3 is a fragmentary front view thereof.

25 Similar letters of reference indicate corresponding parts throughout the several views.

A indicates a wind-chest of any ordinary or well-known construction, and B one of the motor-pneumatics of the piano-action which 30 is controlled by the customary tracker-board and perforated music-sheet. (Not shown in the drawings.)

c indicates one of the hammers of the mandolin-action arranged on the rear side of the 35 wind-chest A and carried by an upright lever C, pivoted at its lower end upon a longitudinal rod d. This rod is mounted in a horizontal supporting-bar E, extending lengthwise of the instrument.

40 F is an actuating or vibrating device for swinging the several hammer-levers in one direction, preferably away from the strings.

The device shown in the drawings consists of a rotary horizontal drum or cylinder arranged immediately below said levers and having annular rows of trip pins or projections f, one row for each lever. These pins are adapted to trip over a wear plate or tongue g, secured to the lower end of the 45 hammer-lever on the rear side of its pivot.

The rearward stroke of the hammer-lever is effected by a spring h, preferably a coil-spring, having one of its branches secured to the front side of the hammer-lever and the 50 other to a vertically - swinging controlling-lever I. The latter is fulcrumed between its

ends, preferably on the same pivot-rod d as the hammer-lever, as shown.

The lever I has a longitudinal slot i, in which the lower end of the hammer-lever 6c plays, and this slot is so arranged that when the rear arm of the controlling-lever is raised the rear end of the slot bears against the adjacent edge of the hammer-lever and causes it to swing upward with the controlling-lever 65 sufficiently to withdraw its tongue from the path of the pins f. The controlling-lever is normally held in the last-named position by a spring j, secured at its lower end to the supporting-bar E and at its upper end to the 70 front arm of the controlling-lever. The front arm of the controlling-lever is depressed by the movable board of one of the motor-pneumatics B or equivalent means. In the construction shown the movement of 75 the pneumatic is transmitted to the controlling-lever by a rod or sticker K.

The upward stroke of each controlling-lever I is preferably limited by a button l, arranged above its front arm and carried by an 80 adjusting-screw l', the adjusting-screws of the several controlling-levers being mounted in a horizontal bar L, extending across the same.

It will now be understood that the rear 85 arm of the controlling-lever is normally elevated, holding the hammer-lever out of the path of the pins of the actuating-cylinder F, as shown in Fig. 1. When, however, the corresponding motor - pneumatic is collapsed, 90 the front arm of the controlling-lever is elevated and its rear arm depressed, whereby the tongue of the hammer-lever is brought into the path of said actuating-pins. While the parts remain temporarily in this position, 95 which is shown in Fig. 2, the hammer is rapidly vibrated by the alternate action of the pins f and the spring h in an obvious manner, causing the hammer to strike the string repeatedly for every note and producing a 100 mandolin effect. As soon as the pneumatic is expanded in a manner common to such piano-actions, the spring j lowers the front arm of the controlling-lever, lifting the hammer-lever out of engagement with the actuating-cylinder F and allowing the hammer to remain at rest until the corresponding pneumatic is again collapsed. 105

The hammer-actuating cylinder may be driven by any suitable means. In the construction shown in the drawings it is driven from a shaft M by a belt m and pulleys m' m'',

said shaft being driven in turn from an electric motor N by worm-gearing n n'.

The spring h, which swings the hammer-lever against the string, is arranged on the 5 upper side of the controlling-lever I, where it is easily accessible for adjusting or renewing it, when required.

I claim as my invention—

1. In a musical instrument of the character 10 described, the combination of a vibrating device, a hammer-lever pivoted adjacent to said device and having a projection adapted to be engaged thereby for swinging said lever in one direction, a controlling-lever movable 15 toward and from said vibrating device and having a part which engages the hammer-lever for withdrawing said projection out of engagement with the vibrating device, a spring acting to swing the hammer-lever in 20 the opposite direction and arranged on the upper side of the controlling-lever, means for normally withdrawing the controlling-lever from the vibrating device, and means for moving the last-named lever toward said device, substantially as set forth.

2. In a musical instrument of the character 25 described, the combination of a vibrating device, a hammer-lever arranged above said device and provided with a projection adapted 30 to be engaged thereby for swinging said lever in one direction, a vertically-swinging controlling-lever also arranged above said vibrating device and having a part arranged to bear against the rear side of the hammer-lever to 35 cause the same to swing upward with the controlling-lever, a spring acting to swing the hammer-lever in the opposite direction and arranged on the upper side of the controlling-lever, means for normally withdrawing the 40 controlling-lever from the vibrating device, and means for moving the last-named lever toward said device, substantially as set forth.

3. In a musical instrument of the character 45 described, the combination of a vibrating device, a hammer-lever arranged above said device and provided with a projection adapted to be engaged thereby for swinging said lever in one direction, a vertically-swinging controlling-lever also arranged above said vibrating device and having a part arranged to 50 bear against the rear side of the hammer-lever to cause the same to swing upward with the controlling-lever, a coil-spring arranged on the upper side of the controlling-lever and having its branches connected to the latter 55 and the hammer-lever, means for normally withdrawing the controlling-lever from the vibrating device, and means for moving the last-named lever toward said device, substantially as set forth.

4. In a musical instrument of the character 60 described, the combination of a vibrating device, a hammer-lever pivoted above said device and having a projection adapted to be engaged thereby for swinging said lever 65 in one direction, a spring for swinging the hammer-lever in the opposite direction, a controlling-lever also arranged above said vibrating device and having a part which engages the hammer-lever and compels the 70 same to move away from the vibrating device with the controlling-lever, a spring for normally withdrawing the controlling-lever from the vibrating device, and a motor-pneumatic connected with the controlling-lever to 75 move the same toward the vibrating device, substantially as set forth.

Witness my hand this 20th day of October, 1905.

EUGENE DE KLEIST.
